DESIGN FOR AN ELECTRIC VIBRATOR

Kenneth F. Lees, New York, N. Y., assignor to
The Olympic Industrial Corporation, New
York, N. Y., a corporation of New York

Application January 31, 1934, Serial No. 50,566

Term of patent 14 years

To all whom it may concern:

Be it known that I, KENNETH F. LEES, a citizen of the United States, residing at New York, in the county and State of New York, have invented a new, original, and ornamental Design for Electric Vibrators, of which the following is a specification, reference being had to the accompanying drawing, forming part thereof.

Fig. 1 is a plan view of an electric vibrator showing my new design;

Fig. 2 is an elevational view of the same; and

Fig. 3 is an end view of the same.

I claim:

The ornamental design for an electric vibrator, as shown.

KENNETH F. LEES.
